UNITED STATES PATENT OFFICE.

JOHN J. EGAN, OF NEW YORK, N. Y.

MASSAGE DEVICE.

No. 923,158.

Specification of Letters Patent.

Patented June 1, 1909.

Application filed July 2, 1908. Serial No. 441,603.

To all whom it may concern:

Be it known that I, JOHN J. EGAN, a citizen of the United States, and resident of New York city, county of New York, and State of New York, have invented certain new and useful Improvements in Massage Devices, of which the following is a specification, reference being had to the accompanying drawing, forming a part thereof, in which similar letters of reference indicate corresponding parts.

This invention relates to massage devices; the object of the invention being to provide a device of this character which embodies an efficient means for massaging the scalp and face, and which may also be employed to massage any part of the human body without liability of injury to the skin.

The device is simple in construction, inexpensive, durable and continuously effective in operation, and it is especially adapted for use in administering self massage treatment.

The invention will be hereinafter fully described and specifically set forth in the annexed claims.

In the accompanying drawings forming part of this specification, Figure 1, is a perspective view of one form of my improved device; and Fig. 2, is a longitudinal sectional elevation taken on the line 2—2, of Fig. 1.

In the practice of my invention as disclosed by the example thereof illustrated in the drawings, I employ primarily a block A, composed of soft, high grade white rubber, for instance a quality of rubber called by the trade "velvet rubber". The said block has a smooth surface *a*, for frictional contact with the epidermis. This block is secured to a base or back B, composed of wood, celluloid or other suitable material, which is preferably supplied with a handle *b*.

In the construction of my invention illustrated by the drawings the said base B, has an upper surface embodying a horizontal plane, and the block of rubber A, has a flange *t*, extended from and surrounding its lower edge, said flange engaging an endless clamp D, which is secured to the base or back B, by means of the screws E, whereby the rubber block A, may be held securely in place or removed and renewed when desirable.

The upper or contact surface *a*, of the rubber block A, is perfectly smooth, and it is preferably slightly curved inwardly to conform to the outward curves of the human body, but it may also be made perfectly flat.

It is a well known fact that massage, properly applied, induces circulation of the blood, and as a consequence causes certain beneficial physiological changes upon the surface of and beneath the skin. This treatment is very beneficial when applied to the head and scalp. I have found by practical experience that my invention is especially useful for scalp and face massage, as it not only causes circulation, but also acts as an efficient cleansing agent; it removes gloss from the scalp and face; opens the pores and causes such local stimulation beneath the skin of the scalp as to actually induce the growth of hair in places where the same has fallen out.

In the operation and use of the invention the operator places the smooth surface *a*, over the surface of the body to be operated upon, and in frictional contact therewith, then by rubbing said surface over the portion of the body being operated upon the beneficial results are attained.

It will be noted that owing to the extended area and smooth contact surface of the rubber block the same takes firm hold on the cuticle and causes the same to be slightly moved back and forth and also cleansed, the deleterious foreign matter being rubbed off and absorbed by particles of the rubber block surface which are released by the frictional action, said action at the same time stimulating the true skin and the flesh beneath because of the induced circulation of the blood.

The device when applied to a smooth, shiny, bald scalp and forehead almost immediately removes the gloss therefrom, and by constant application not only loosens up the abnormally tightly drawn skin over the scalp, but so stimulates the portions beneath as to actually cause new hair to grow, of course provided the roots are not entirely dead. The application of the device also maintains the scalp and face in a non-shiny and perfectly clean condition.

I am aware that rubber brushes having roughened contact surfaces are not new, I therefore, do not claim broadly a rubber brush.

Having thus described my invention, what I claim as new, and desire to secure by Letters Patent, is:

1. In a massage device, the combination, with the back having an extended handle, of the solid rubber block having the smooth, concave upper surface and a base flange; of the back, and the ring fitting over the said

flange and secured to said back, and means securing the ring to the back, substantially as shown and described.

2. As a new article of manufacture, the massaging device comprising the solid rubber block having the bottom flange and the smooth, concave upper surface for contact with the human body, and the back therefor having the handle and the ring connecting the said block and back to each other, and

means connecting said parts, substantially as shown and described.

In testimony that I claim the foregoing as my invention, I have signed my name in presence of two witnesses, this 29th day of June 1908.

JOHN J. EGAN.
